UNITED STATES PATENT OFFICE.

WILLIAM U. GRIFFITHS, OF PHILADELPHIA, PENNSYLVANIA.

VALVE-OPERATING MECHANISM FOR WATER-CLOSET APPARATUS.

1,165,591.

Specification of Letters Patent. Patented Dec. 28, 1915.

Application filed September 2, 1914. Serial No. 859,741.

To all whom it may concern:

Be it known that I, WILLIAM U. GRIFFITHS, a citizen of the United States, and a resident of Philadelphia, in the county of

5 Philadelphia and State of Pennsylvania, have invented certain new and useful Improvements in Valve-Operating Mechanism for Water-Closet Apparatus, of which the following is a specification.

10 My invention relates to an improvement in valve operating mechanism for water closet apparatus, and it has for its object to provide an improved construction of means for actuating the valves which control the 15 supply of water to the flush tank, and the flow of water from the latter to the closet bowl.

In order that my invention may be clearly and readily comprehended, reference should 20 be had to the accompanying drawing in which I have illustrated one form of a convenient embodiment of my invention, it being understood, however, that changes in the details of construction may be made 25 within the scope of the claims without departing from the same.

In the drawings, Figure 1 is a side elevation of a water closet apparatus provided with my invention, a portion of the closet 30 being broken away and shown in section; Fig. 2 is a vertical longitudinal sectional view showing the construction of valve mechanism, the means for operating the same and the connections from the source 35 of supply to the flush tank and to the closet bowl or hopper; Fig. 3 is a transverse section on the line 3—3 of Fig. 2; and Fig. 4 is a transverse section on the line 4—4 of Fig. 2.

40 Referring to the drawings, 1 designates a closet bowl seated upon the floor 2 or other suitable support, and 3 designates a soil pipe leading therefrom.

45 4 designates a pipe for supplying water from any source of supply to the flush tank 5; and 6 designates a waste pipe by means of which water may escape from the pipe 4 into the waste or soil pipe 3.

50 10 designates a valve situated in the supply pipe 4 at a point below the waste pipe 6.

The design as illustrated is adapted for use in connection with water closet apparatus so situated as to be subject to freezing winter temperature, but it will be understood 55 that it may be used upon or in connection with other structures which are situ-

ated inside of houses or other structures which are heated so that there would be no danger of freezing the water which might be retained in the pipes.

60

11 designates a branch pipe extending laterally from a coupling 11^a which is interposed in and forms in effect a part of the supply pipe 4.

12 designates a pipe or coupling by means 65 of which the branch pipe 11 is connected and put into communication with the closet bowl 1.

13 designates a plate extending across the branch pipe 11 and provided with an opening 14 which is adapted to be closed by means of a valve 15 supported upon a longitudinally movable rod 15^a; the front end of which projects through and is guided by a cap 16 which closes the outer end of the 75 branch pipe 11.

In order to effect a complete air and water tight closure of the outer end of the branch pipe 11, I have provided a gum or rubber sheet 17, the outer edges of which 80 are clamped between the cap 16 and the outer end of the said pipe 11, while the inner portion of the said sheet 17 is secured to the rod 15^a in known manner as illustrated in Fig. 2 of the drawings. The rear 85 inner end portion of the rod 15^a extends through a guiding opening 18 formed in a cross piece 19, situated inside of the branch pipe 11. It may be noted that the transverse plate 13 is situated adjacent to and in 90 rear of the point of connection of the pipe or coupling 12 with the branch pipe 11.

20 designates a lever of bell crank form pivoted at 21 to a rod extending across the coupling 11^a. One arm 22 of the said lever 95 extends downwardly into operative relation to the rear end of the rod 15^a. The other arm 23 of the said lever projects rearwardly upon opposite sides of the rod 24 to which the valve 10 is connected, the said arm 23 100 being bifurcated for that purpose. The rod 24 is provided with a sleeve 25 which is situated above and in proximity to the upper side of the arm 23 of the lever 20.

27 designates a rod extending beyond the 105 sleeve 25 in alignment with the rod 24, and projecting through a hole in a bar 28 extending across the pipe 4. The rod 24 is normally held in its lowermost position with the valve 10 closed by the action of the 110 coiled spring 30 which is coiled around the rod 27 with its upper end bearing against

the bar 28, and its lower end resting upon the sleeve 25. Normally, the closet seat 31 occupies the position illustrated in Fig. 1 of the drawings, but when depressed the rear 5 slightly projecting arm or lever 32 secured thereto and which rests against the front end of the rod 15^a, causes longitudinal movement of the latter toward the rear, so as to cause the valve 15 to contact with the 10 plate 13 and close the valve opening 14. Simultaneously, the bell crank lever 20 is rotated about its pivot 21 so that its rearwardly extending arm 23 is raised. The said arm contacting with the lower side of 15 the sleeve 25, causes upward movement thereof against the tension of the spring 30 to lift the rod 24 and the valve 10 to open the latter, so that water may pass through the supply pipe 4 and through the valve 10 into the flush tank 5. The seat is caused 20 to return to the position indicated in Fig. 1 by the action of the spring 30, which acting through the sleeve 25 upon the lever 20 causes rotations of the latter and consequent 25 outward or forward movement of the rod 15^a. In this way, the valve 10 is closed, while the valve 15 is simultaneously opened. The opening of the latter valve permits the water which has entered the flush tank 5 30 to flow rapidly down the upper portion of the supply pipe 4 and through the branch pipe 11 and the coupling pipe 12 into the closet bowl or hopper to flush and cleanse the same.

35 I claim:—

1. The combination of a valve for opening and closing a supply pipe the said valve having connection with a rod extending longitudinally of the said supply pipe, a spring 40 for holding the said valve and rod in depressed position, a bell crank lever pivoted intermediate the ends at a point near and intermediate the ends of the said rod one arm of the said lever extending at right 45 angles to said rod and being in engagement therewith, a branch pipe having connection with the said supply pipe the said branch pipe having a plate extending across the same such plate being provided with an

opening, a longitudinally movable rod extending longitudinally of said branch pipe and being supported therein and thereby, the said rod being provided with a valve which is adapted to open and close the opening in the said plate and the rear end of 55 the said rod occupying a position in operative relation to the other arm of said bell crank lever, and means for effecting longitudinal movement of the said longitudinally movable rod substantially as and for the 60 purpose described.

2. The combination of a supply pipe, a valve for opening and closing said pipe said valve having connection with a rod extending longitudinally of the said supply pipe, means for holding the said rod normally in depressed position to close the 65 said valve, an angular lever pivoted independently of and intermediate the ends of said rod and having one of its arms extending transversely of the said rod and in engagement therewith, a branch pipe extending laterally from the said supply pipe and having a plate extending transversely thereof of which plate is provided with an opening, 70 a rod supported by and extending longitudinally in the said branch pipe said rod being provided with a valve for closing the opening in the said plate and the inner rear end of the said rod being in operative relation to the other arm of the said angular 75 lever, and means upon the closet seat of the apparatus for contacting with the front end of the said longitudinally movable rod when the seat is depressed to occasion rearward 80 longitudinal movement of the said rod to thereby occasion pivotal movement of the said angular lever to lift the rod in the said supply pipe substantially as and for the 85 purpose described.

90 In testimony that I claim the foregoing as my invention, I have hereunto set my hand this 18th day of August, A. D. 1914.

WILLIAM U. GRIFFITHS.
